(57) **CLAIM**

The ornamental design for an “upper-piping visor,” as shown and described.

DESCRIPTION

FIG. 1 is a perspective view of “upper-piping visor” showing my new design;

FIG. 2 is a front elevational view thereof;

FIG. 3 is a bottom plan view thereof;

FIG. 4 is a left elevational view of thereof; and,

FIG. 5 is a right elevational view of thereof.

The darker portion of the visor represents a difference in color

The broken line showing of the crown is for illustrative purposes only and forms no part of the claimed design.
